UNITED STATES PATENT OFFICE.

LESLIE S. CUSHMAN, OF LINCOLN, NEBRASKA.

SPARKING MECHANISM FOR INTERNAL-COMBUSTION ENGINES.

No. 866,001.

Specification of Letters Patent.

Patented Sept. 17, 1907.

Application filed June 3, 1907. Serial No. 377,102.

To all whom it may concern:

Be it known that I, LESLIE S. CUSHMAN, a citizen of the United States, residing at Lincoln, in the county of Lancaster and State of Nebraska, have invented a new and useful Sparking Mechanism for Internal-Combustion Engines, of which the following is a specification.

This invention relates to ignition apparatus for internal combustion engines, and has for its principal object to provide means whereby a single sparking or induction coil may be used in connection with two or more sparking plugs, thus reducing the expense of installation and wiring, and at the same time making the device more compact.

15 A further object of the invention is to provide a sparking apparatus in which the secondary of the induction coil or circuit of the sparking coil may be connected alternately to the plugs of a double cylinder engine.

20 With these and other objects in view, as will more fully hereinafter appear, the invention consists in certain novel features of construction and arrangement of parts, hereinabove fully described, illustrated in the accompanying drawings, and particularly 25 pointed out in the appended claims, it being understood that various changes in the form, proportions, size and minor details of the structure may be made without departing from the spirit or sacrificing any of the advantages of the invention.

30 In the accompanying drawings:—Figure 1 is a side elevation of a sparking mechanism constructed in accordance with the invention. Fig. 2 is a transverse sectional view of the same on the line 2—2 of Fig. 1. Fig. 3 is a diagram of the wiring connection.

35 Similar numerals of reference are employed to indicate corresponding parts throughout the several figures of the drawings.

The device is intended for use in connection with two cylinders A and B, having sparking plugs C—D, 40 respectively. At any convenient point is arranged an induction coil E, the primary of which is connected in circuit with a suitable battery and spark timer or similar circuit controller. At any suitable point on or adjacent to the engine is secured a box or casing 10

formed of insulating material and carrying at the front 45 a number of binding posts 11, 12 and 13, the binding post 11 being connected to the spark plug C, the binding post 12 to the spark plug D, and the binding post 13 to the secondary of the coil. The stems of the binding posts extend through the wall of the casing 50 and carry contact plates 14, 15 and 16, respectively, the contact plate 16 being in the form of a curved strip that is arranged, on an arcuate line struck from the center of a shaft 17 that is journaled in bearings in the lower part of the casing.

55 Secured to the shaft 17 is an arm 18 formed of insulating material and carrying a metallic plate 19, the lower end of which is constantly in engagement with the contact 16, and which may be moved to alternately place said contact plate in circuit with the contact plate 14, and contact plate 15, so that the secondary of the circuit will be alternately connected to the sparking plugs. At a point outside the casing the shaft 17 carries a rocker arm 21 that is connected by a rod 22 to an eccentric strap 23 surrounding an eccentric 60 24 on a shaft 25, which shaft may be the main shaft of the engine or may be operatively connected to the engine in any manner.

65 A distributing switch constructed in accordance with this invention may be readily placed on the side 70 of one of the cylinders and operated from the crank shaft without the necessity of employing any gearing or other intricate connecting mechanism.

I claim:—

75 In apparatus of the class described, a box or casing, contact plates arranged therein, one adapted to be connected to the terminal of a sparking circuit, and the others to the terminals of the sparking plugs, a shaft mounted in the casing, a rocker arm carried by the shaft, a contact plate carried by the arm and insulated from the shaft, said contact plate being constantly in engagement with the terminal of the sparking circuit, and mechanism for rocking the shaft to move the plate alternately into engagement with the contact plates of the plugs.

80 In testimony that I claim the foregoing as my own, I 85 have hereto affixed my signature in the presence of two witnesses.

LESLIE S. CUSHMAN.
